Patented Nov. 16, 1965

202,870

WASH BASIN UNIT

David Charles Kirby, 28 Warren Way,
Digsowell, Welwyn, England

Filed Dec. 1, 1964, Ser. No. 82,853

Claims priority, application Great Britain June 1, 1964

Term of patent 14 years

(Cl. D4—2)

Fig. 1

The exterior of the unit is intaglio with the interior, as indicated by FIGURE 3.

I claim:

The ornamental design for a wash basin unit, substantially as shown and described.
